ROCK DRILL

Mervin Chester Huffman, Claremont, N. H., assignor to Sullivan Machinery Company, a corporation of Massachusetts

Application February 21, 1931, Serial No. 517,521

3 Claims. (Cl. 121—7)

This invention relates to rock drills, and more particularly to improved drill steel rotation mechanism for rock drills of the hammer type.

An object of this invention is to provide an improved rock drill rotation mechanism. A further object is to provide an improved drill steel rotation mechanism for a rock drill of the hammer type having embodied therein improved release means for such rotation mechanism. Still another object is to provide in a rock drill of the hammer piston type improved drill steel rotation mechanism of the intermittent ratchet and pawl type operated by the hammer piston of the drill and having embodied therein improved release means for the rotation mechanism whereby, when desired, rotation of the drill steel may be discontinued while the hammer piston continues to operate. Still another object is to provide an improved pressure fluid governed friction control for a rock drill rotation mechanism. These and other objects and advantages of this invention will, however, hereinafter more fully appear.

In the accompanying drawings, in which I have shown for purposes of illustration one embodiment which the invention may assume in practice,—

Fig. 1 is a side elevational view of a rock drill of the stoper type in which the illustrative embodiment of the invention is incorporated.

Fig. 2 is a longitudinal axial sectional view on the line 2—2 of Fig. 1.

Fig. 3 is a section taken through the axis of the rotation handle, so called.

Fig. 4 is a transverse section on the plane of the line 4—4 of Fig. 2.

Fig. 5 is a transverse section on the plane of the line 5—5 of Fig. 2, through the ratchet mechanism.

Referring to the drawings, Fig. 1 shows a rock drilling motor generally designated 1 and comprising a cylinder 2 within which a hammer piston 3 is mounted for reciprocation. This hammer piston is provided with a striking bar 4 having splineways 5 therein by which rotation is adapted to be imparted through any suitable chuck mechanism housed within a chuck housing 6, to a rock drill steel 7. The fluid supply to the drilling motor is from an air line 8 and under the control of a throttle valve mechanism 9, and fluid distribution to the motor is effected through a sleeve valve 10 mounted within a valve chest 11 formed in a member 12 mounted at the rear end of the cylinder. The member 12 supports the throttle valve mechanism 9 and also has a boss 13 within which the handle member 14, held by the

drill runner, is secured. Rotation of the piston 3 is effected by means of a ratchet controlled system of elements including a forwardly extending rifle bar 16 having spiral grooves 17 therein, which cooperate with a rifle nut 18 threadedly mounted in the rear end of the piston 3. At its rear end the rifle bar 16, which extends coaxially through the valve 10 and a closure member 19 for the valve chest, is formed with a pawl carrying portion 21. This portion carries a series of pawls 22 resiliently pressed toward ratchet engaging position by plungers 23 and springs 24, and the pawls 22 are adapted to engage a series of ratchet teeth 25 formed within a ratchet ring member 26. This member is rotatably supported within a chamber forming member 27 positioned to the rear of the valve chest head member 19 and has a cylindrical periphery 28 guided within a cylindrical bore 29 formed within the member 27. The ratchet ring member 26 has a rearwardly projecting hollow boss 30 within whose interior a projection 31, upon the rifle bar member, is rotatably supported, and whose exterior periphery is provided with a series, herein four, of longitudinal grooves 32. The bore 29 in the member 27 is of reduced diameter at its inner portion 34, and permitting a slight longitudinal movement under certain conditions, is provided with a number of longitudinally extending internal grooves 35 extending lengthwise of this reduced bore. A series of friction brake discs 36 and 37, having thereon ears designated respectively 38 and 39, are assembled within the reduced bore 34, surrounding the boss 30, the discs 36 engaging, through their ears and the grooves 35, the member 27; and the grooves 32 and ears 39 holding the discs 37 in non-rotative relation to the boss 30. A follower or brake loading member 40 is placed at the end of the reduced bore 34 remote from the motor. The member 26 is slightly shorter than the distance between the closure member 19 and the shoulder at the rearward end of the full-sized bore 29, and the member 40 has a slightly greater potential movement. Provision is made whereby pressure may be applied to the follower member 40 to effect frictional engagement of the brake discs, and resultant holding stationary at will of the ratchet member 26. For this purpose a cylindrical bore 41 is arranged to the rear of the longitudinally extending grooves 35, and a packing member or cup washer 42 is arranged within this member and in engagement with the follower 40. A passage 43, to which fluid is supplied through a port 44 in the throttle valve, serves to admit fluid to apply pressure to the brake discs, and relieving of the

pressure upon these discs is made possible by a vent passage 46 and a vent valve 47 arranged within the handle 14, the valve 47 being recipro-
5 cable in a bore 43 in the handle and normally held by a spring 49 in a position to prevent com-
munication between a port 51 in the plunger and a port 52 opening to atmosphere. By restricting the fluid supply as at 43^a control is much facil-
10 tated, and free reciprocation without rotation for spotting is possible. The usual cleansing fluid supply tube 54 is mounted in a gland member 55 at the rear end of the member 27, and a feed cylinder 56 is held in assembled relation with the several parts of the drilling motor by a collar 15 57 and side rods 58 whose forward ends carry nuts 59 which cooperate with lock washers 60.

From the foregoing description so far given, the mode of operation of this mechanism will be clearly apparent. It will be evident that the piston 3 will not rotate if the ratchet ring 26 is free to rotate, but that upon holding of the ratchet ring stationary, rotation will be imparted to the piston 3 and thus to the hollow drill steel 7. Upon appropriate adjustment of the throttle valve 20 mechanism 9 air admitted from the pipe or connection 8 to the passage 43 through the port 44 will act upon the rear surface of the cup washer 42 and press the brake follower 40 forwardly, thereby effecting a frictional engagement of the 25 discs 36 and 37 and locking the ratchet ring relative to the drill as a whole. During rotation of the drill steel, it will be appreciated that the valve plunger 47 is in the position shown in Fig 3, and that air admitted through the passage 43 is pre-
30 vented from escaping. By moving the plunger 47 inwardly the passage 51 may be caused to communicate with the passage 52 to varying degrees, and by properly proportioning the size of the passages and regulating the degree of communica-
35 tion between ports 51 and 52, a variable degree of locking of the ratchet can be effected, the ratchet being practically freed from free rotation, or variably retarded from rotation as desired by a suitable manipulation of the plunger 47. During
40 "spotting" no rotation, or very slow rotation is desirable, and by the present mechanism any desired condition can be attained. The play of members 26 and 40 permits complete loosening of the friction discs, and on release of the air during heavy rotation, the rearward motion of the piston under full air pressure will instantly relieve the friction.

A plurality of friction discs are provided and when the discs are interleaved in alternate relation as shown in Fig. 2, the maximum possible frictional resistance is imparted to the ratchet ring. However, to suit varying conditions, the interleaved relation of the discs may be changed so that maximum frictional resistance of a smaller degree may be imparted to the ratchet ring; for instance, when a minimum resistance is desired, all the discs 36 are placed together and held stationary with the casing while the discs 35 are all placed together and secured to the ratchet ring, so that the frictional effect is that of but two discs and the frictional resistance will be comparatively slight. By varying the interleaving different braking effects can be secured and the desired results obtained. It will be evident that when the 70 rotation parts become overloaded the friction is so designed as to slip, thereby preventing possible breakage of the parts.

From the foregoing description it will be observed that I have provided a very simple and 75 convenient apparatus for controlling the rotation

of a drilling motor, and that a readily varied rate of rotation, or rotation at maximum speed, or no rotation at all, may be effected at will. It will be noted, moreover, that the mechanism is entirely free from any cam devices or the like re-
quiring adjustment and complicated construction, and that by the mere manipulation of a conveniently disposed valve plunger, the desired control may be effected. These and other advantages of the invention will be clearly apparent to those skilled in the art.

While there is in this application specifically described one form which the invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a rock drilling mechanism, the combination with a drill steel actuating motor including a hammer piston, of drill steel rotation mechanism operated by said hammer piston including an oscillatory pawl carrier, a rotatable ratchet ring having teeth with which the pawls of said carrier are engageable, said ratchet ring having a rearward cylindrical portion having formed therein bearing means and said pawl carrier having a rearward bearing portion journaled in said bearing means, and a frictional braking device for yieldingly holding said ratchet ring against rotation including friction discs connected to the portion of the ratchet ring surrounding said bearing means and the rearward bearing portion of the pawl carrier, friction discs connected to a relatively stationary element of the drill and interleaved with said friction discs, and means operable at will for forcing said discs together 105 into frictional engagement to hold yieldingly said ratchet ring against rotation thereby to effect drill steel rotation or to permit slippage or release of said discs to vary the rotation of the ratchet ring or to release entirely said ratchet ring for free 110 rotation.

2. In a rock drilling mechanism, the combination with a drill steel actuating motor including a hammer piston, of drill steel rotation mechanism operated by said hammer piston including an oscillatory pawl carrier, a rotatable ratchet ring having teeth with which the pawls of said carrier are engageable, said ratchet ring having a rearward cylindrical portion having formed therein bearing means and said pawl carrier having a rearward bearing portion journaled in said bearing means, and a frictional braking device for yieldingly holding said ratchet ring against rotation including friction discs connected to the portion of the ratchet ring surrounding said bearing means and the rearward bearing portion of the pawl carrier, friction discs connected to a relatively stationary element of the drill and interleaved with said friction discs, and means operable at will for forcing said discs together 130 into frictional engagement to hold yieldingly said ratchet ring against rotation thereby to effect drill steel rotation or to permit slippage or release of said discs to vary the rotation of the ratchet ring or to release entirely said ratchet ring for free 135 rotation and including a disc-like plunger arranged at the rear of said bearing portion of the ratchet ring and engaging the rearmost of said discs, said stationary part of the drill having a guide bore for said plunger.

3. In a rock drilling mechanism, the combination with a drill steel actuating motor including a hammer piston, of drill steel rotation mechanism operated by said hammer piston including 5 an oscillatory pawl carrier, a rotatable ratchet ring having teeth with which the pawls of said carrier are engageable, said ratchet ring having a rearward cylindrical portion having formed therein bearing means and said pawl carrier having 10 a rearward bearing portion journaled in said bearing means, and a frictional braking device for yieldingly holding said ratchet ring against rotation including friction discs connected to the portion of the ratchet ring surrounding said 15 bearing means and the rearward bearing portion of the pawl carrier, friction discs connected to a relatively stationary element of the drill and interleaved with said friction discs, and means operable at will for forcing said discs together 20
- into frictional engagement to hold yieldingly said ratchet ring against rotation thereby to effect drill steel rotation or to permit slippage or release of said discs to vary the rotation of the ratchet ring or to release entirely said ratchet ring for 25 free rotation and including a disc-like plunger arranged at the rear of said bearing portion of the ratchet ring and engaging the rearmost of said discs, said stationary part of the drill having a guide bore for said plunger, and fluid means for actuating said plunger including an aligned bore formed in the stationary part of the drill, a packing member engaging the walls of said latter bore and said plunger for actuating the latter and means for supplying fluid to said latter 30 bore to act on said packing member. 80 85 90
